(57) **CLAIM**

The ornamental design for an light source of light emitting diode, as shown and described.

DESCRIPTION

FIG. 1 is a perspective view of one embodiment of an light source of light emitting diode showing our design;

FIG. 2 is a top plan view of the light source of light emitting diode shown in FIG. 1;

FIG. 3 is a bottom plan view of the light source of light emitting diode shown in FIG. 1;

FIG. 4 is a front elevation view of the light source of light emitting diode shown in FIG. 1, with the back elevation view being substantially similar; and,

FIG. 5 is a side elevation view of the light source of light emitting diode shown in FIG. 1, with the opposite side elevation view being substantially similar.
